UNITED STATES PATENT OFFICE.

JOHN G. H. LIEBEL, OF CINCINNATI, OHIO, AND THOMAS H. CHERRY, OF NEW YORK,
N. Y., ASSIGNORS TO THE LIEBEL-FLARSHEIM COMPANY, OF CINCINNATI, OHIO,
A CORPORATION OF OHIO.

ELECTRODE.

Application filed August 22, 1927. Serial No. 214,526.

This invention relates to electrodes for the therapeutic application of diathermy (high frequency) currents. These electrodes form two general classes, those intended for surface application, as for instance to the abdomen, chest, foot, etc., and those intended for orificial applications, such as vaginal, prostatic, rectal, etc. This disclosure is made particularly with reference to orificial electrodes, since the problems sought to be solved by this invention are more acute in orificial applications of the diathermy currents.

It is extremely important in many applications to be able to control very accurately the temperature of the tissues being treated. Too low a temperature fails in therapeutic results and too high a temperature, by a matter of only a few degrees, can and often does prove injurious. For instance in treating the mucous membrane that has been infected by gonococci, it is desirable to elevate the temperature of the tissues to an amount higher than the lethal temperature of the bacteria, but still to maintain it below that at which tissue injury takes place. For example at around 103 to 104° F. the gonococcus dies after an hour or more. At 115° F. this particular type of organism is destroyed in from 20 to 30 minutes. At 122° F. the destruction is still more rapid and it is this temperature that is ordinarily used as the highest temperature within tissue tolerance. At 130° F. definite tissue destruction begins to take place and the application becomes quite uncomfortable and painful to the patient. It will be seen therefore that accurate control of the temperature of the tissues immediately surrounding the active electrode becomes of extreme importance if therapeutic results are to be obtained and injury to the patient avoided.

The object of this invention is to provide an electrode for therapeutic application of electrical current, adapted to carry a thermometer which contacts the tissues about the electrode.

Another object of the invention is to provide a sanitary, easily sterilizable thermometer carrying electrode of the class described.

Other objects and certain advantages will be apparent from the description of the accompanying drawings, in which:

Figure 1 is a side elevation of a prostatic electrode.

Figure 2 is a sectional view on line 2—2 of Figure 1.

Figure 3 is a sectional view on line 3—3 of Figure 2.

Figure 4 is a side elevation of a vaginal electrode.

Figure 5 is a sectional view on line 5—5 of Figure 4.

Figure 6 is a sectional view on line 6—6 of Figure 5.

The electrodes disclosed in these drawings comprise a shank piece 1 which is hollow or apertured to provide a passageway for the insertion of a thermometer 2 therethrough. To the end of this shank piece is secured a hollow or shell like electrode tip 3 which is provided with a depression 4 aligned with the thermometer passageway in the shank piece to receive the thermometer bulb 5 and expose the same. The depression is therefore of approximately the depth of the bulb. The tip is preferably of material possessed of low thermal inertia which coupled with the shell like structure avoids any lag in thermometer registry which might be due to heat absorption by the tip.

A metallic stem 6 threaded at both ends, extends through this shank piece and secures the tip to the shank piece. At the other end of the shank piece is a terminal collar 7 to which is secured the current supply wire by means of a set screw 8.

In the prostatic electrode disclosed in Figures 1, 2, 3, the stem is hollow and the thermometer therethrough introduced. In the vaginal electrode disclosed in Figures 4, 5, 6, the shank piece is apertured centrally for the stem and near the edge for the thermometer passageway.

Preferably the shank piece is of hard rubber or other insulating material so that the tip alone constitutes the active electrode.

It is obvious that any temperature measuring means, such as a thermo-couple, may be used as well as the usual mercury thermometer.

While the disclosure has been made in relation to orificial electrodes it is to be noted that the same principles of structure are applicable to body or surface electrodes.

Having described our invention, we claim:

1. An electrode for the therapeutic application of electric current, comprising an apertured shank piece adapted to admit a

thermometer therethrough, and a hollow electrode tip, secured to said shank piece, said tip adapted to expose the thermometer bulb.

2. An orificial electrode for the therapeutic application of electric currents, comprising a shank piece of insulating material, a hollow metallic electrode tip having a depression therein adapted to expose a thermometer bulb, a metallic stem extending through said shank piece securing said shank piece

and tip together, and a passage way extending through said shank piece, said passage way aligned and connected with the depression in said tip to permit the insertion of a thermometer.

15

In witness whereof, we hereunto subscribe our names.

JOHN G. H. LIEBEL.
THOMAS H. CHERRY.
